METHOD OF ATTACHING HEELS TO SHOES

Andrew J. Book, Buena Vista, Ohio

Application March 14, 1935, Serial No. 11,134

2 Claims. (Cl. 12—147)

This invention relates to a method of and a means for attaching heels to shoes and has for its object to provide a method which is simple in operation, as well as a mechanism which is simple in construction, the method and means being more efficient in use than those heretofore proposed.

With these and other objects in view the invention resides in the novel details of construction and combinations of parts constituting the mechanism as well as in the novel steps and combinations of steps constituting the method, all as will be more fully disclosed hereinafter and particularly pointed out in the claims.

15 Referring to the accompanying drawings forming a part of this specification and in which like numerals designate like parts in all the views,—

Fig. 1 is a front elevational view of a device made in accordance with this invention;

20 Fig. 2 is a vertical sectional view taken centrally of the device and showing it in operation upon a shoe;

Fig. 3 is a detail view in vertical section taken as on the line 3—3 of Fig. 1 and looking in the 25 direction of the arrows;

Fig. 4 is a bottom plan view of the clamping bar shown in Fig. 1;

Fig. 5 is a detail elevational view of a modified form of clamping bar; and

30 Fig. 6 is a transverse sectional view taken as on the line 6—6 of Fig. 5 and looking in the direction of the arrow.

This invention is directed to a mechanical device for assisting in the securement of a heel to a shoe, and a method for accomplishing said securement, resulting particularly in a stronger assemblage of heel and sole especially in the construction of women's shoes having relatively high heels. In the drawings 1 represents a last provided with a bore 2 for receiving the work-supporting pin 3 of a jack-post 4 which latter is provided with a suitable base such as 5 slidable in a dovetail track 6 of a base plate 7 bolted as at 8 to a work bench 9, said jack-post thereby being adjustable toward and away from the operator and secured as by the set screw 10 in adjusted position.

50 The shoe includes generally a sole portion consisting of the inner and outer layers 15 and 16, and a heel 17, the latter provided with a bore 18 extending all the way through from bottom to top, said bore being enlarged at the bottom to receive therein a metallic washer 19 for engaging the head of a long screw 20, and enlarged at the 55 top to receive a connector member 21 axially threaded for engagement with the long screw 20. The sole layers 15 and 16 have holes in substantial axial alignment with the bore 18 in order to receive therethrough a short screw 22 threadedly engaging the connector 21, the head of said short

screw seated within a counter-sunk metallic disc or plate disposed between the inner sole layer 15 and the last 1. A pocket 23 is provided in the last in substantial axial alignment with the holes in the sole layers and the bore in the heel, said pocket being of such dimensions as to permit nearly all of the short screw 22 to be confined therein. That is to say, during the shoe assembly the short screw will be in said pocket and will not protrude through the sole layers 15 and 16 to such an extent as to interfere with the mechanical operations incident to the laying and building-up of the sole, the hole in the outer layer 16 being of sufficient diameter to receive one 15 end of the connector 21.

15 In a transverse plane of the base plate 7 and separated by the dovetail track 6 is a pair of vertical guides 25 and 26 threaded into or otherwise secured to said plate, and slidably receiving the rods 27 and 28 respectively therein, the 20 upper extremities of said rods being rigidly connected by a heel clamping bar 29. This bar is provided with an opening 30 in the central portion thereof, said opening being transversely of such dimension as not only to substantially register with the axial bore 18 in the heel 17 of the shoe, but to permit the long screw 20 to be passed entirely through said opening and turned into the connector 21, a screw driver or other suitable 25 tool being utilized for this purpose. The portion of this bar adjacent the opening 30, as seen in Figs. 1, 2 and 4, is provided with a surface 31 which is in such a plane as to permit said surface to contact the lower surface of the heel 17 when the bar is brought into contact therewith 30 as will be described presently.

The lower extremities of the rods 27 and 28 are rigidly connected by the cross bar 32 beneath the base plate 7, said plate serving as a stop, 40 limiting the upward movement of said rods. As best seen in Fig. 2, this cross bar 32 at its central portion has rigidly depending therefrom a hook 33 the long shank 34 of which passes through a guide bracket 35 secured to the underside of 45 the base plate, this bracket preferably being of U-shape whereby a coil spring 36, enclosing the shank 34, may be interposed between the inner surface of the bracket and the under surface of the cross bar to force the latter upwardly, as 50 will be readily understood. The hook 33 is connected as by the link 37 to a suitable lever or pedal which when operated will cause the clamping bar 29 to be moved downwardly into contact with the heel 17 of the shoe carried by the last 55 1 mounted upon the jack-post 4.

The dovetail track 6 is preferably provided to permit adjustment of the jack-post, since women's shoes are made with heels of different heights and different angles of inclination to the 60 sole, whereby this construction makes it possible

to set the jack-post in proper position to bring the bore through the heel into axial registration with the opening 30 of the clamping bar 29 for final securement of the heel to the shoe. Also 5 mounted in the dovetail track 6 is a carrier 40 securable in adjusted position as by the set screw 41, said carrier having an upwardly extending bracket arm 42 preferably slotted to adjustably receive the bolt 43 by which a companion bracket arm 44, carrying a toe rest 45 at its upper extremity, may be adjusted as to height above the base plate, said toe rest being preferably curved or of U shape to receive therein and steady the toe portion of the shoe during 15 the heel securing operation. The adjustability of this toe rest is provided because of the different styles of shoes handled by this mechanism.

In Figs. 5 and 6 are shown one form of modified heel clamping bar, wherein the bar 50 has 20 trunnion ends such as 51 rotatable or rockable in bores provided in the upper ends of the slideable rods 27 and 28, the ultimate position of the bar 50 being adjustably secured by set screws such as 52. The central portion of this bar is 25 provided with a groove or cut-away surface portion 53 for engagement with the surface of the heel, but the surface of this groove may be formed parallel to a face of the bar since the latter may be rocked or turned, through its trunnion engagement with the rods 27 and 28, to bring said surface into the plane of the heel, Fig. 6 showing in dotted lines an adjusted position of said bar. Obviously other modifications 30 of the adjustability of this cross bar may be had 35 including the omission of the set screws 52 but providing the surface of the ends 51 of said bar with longitudinally extending ridges or teeth adapted to engage correspondingly formed ridges or teeth on the inner surface of the upper ends 40 of the rods 27 and 28, this construction permitting adjustability in predetermined positions whereas the set screws 52 and smooth surfaces of the trunnion bearings shown in Fig. 5 permit any adjustability desired.

45 The method of securing the heel to the shoe is as follows. Upon the last 1 is laid the necessary sole layers such as 15 and 16 with the openings therein in registry with the pocket 23 of the last, and the short screw 22 with its associated 50 counter-sunk washer disc interposed between the layer 15 and the bottom of the last, said short screw dropping by gravity into said pocket, it being understood that the last will be in inverted position as shown in Fig. 2. The last with the 55 sole layers may then be subjected to the operations of the lasting machine, sole laying, leveling, and subsequently to the welt machine, and trimming machine during the further building-up of the shoe structure, without interference 60 from the short screw because the latter by virtue of the pocket 23 is permitted to occupy such a position as to prevent it from extending upwardly into the way of the machine parts.

The shoe, still on the last 1, is then taken 65 to the heelng room where the heel is applied to the shoe. The heel naturally has been provided with the bore 18 and just previously to placing the heel on the shoe the usual coat of glue is applied to the surface of the sole and to 70 the heel seat, the glue being permitted to enter the enlarged portion of the bore adjacent the heel seat. The connector 21 is then screwed onto the end of the short screw 22 until the latter has been worked upwardly out of the pocket

23 with the head of the screw contacting the counter-sunk portion of the disc washer. The outer surface of the connector is roughened, as by grooves shown in Fig. 2, so that when it ultimately is passed into the enlarged end of the 5 bore 18, the glue therein will enter said grooves and, upon drying, tend to key and anchor said connector in final position.

The heel is then applied to the shoe with the connector entering the portion of the bore provided therefor and then the long screw 20 is passed down through the bore and threaded into the connector. During this operation the heel correctly positions the heel upon the sole and then operates the lever or foot pedal to move 15 the heel clamping bar 29 downwardly upon the heel and, while the pressure of said clamping bar is still upon the heel, a screw driver or other suitable tool is passed through the opening 30 of the bar and operated to thread the long screw 20 into the connector 21 to permanently secure the heel to the shoe, the head of the long screw ultimately coming into seated position on the metallic washer 19. The pressure of the clamping bar may then be released and, after the glued 25 joint has hardened, the usual top lift not shown may be applied to the bottom of the heel to cover the head of the screw 20.

From the foregoing description it will thus be seen that by this invention there is provided a 30 means for, as well as a method of, securing a heel to a shoe. The screws 20 and 22 together with the connector 21 constitute tensioning members for fastening the heel to the sole. The jack-post 4 together with the last 1 and the clamping bar 29 constitutes a means for applying pressure to the heel while it is positioned upon the sole; thus making it possible to lock the members 20, 21 and 23 under tension while the pressure is applied. Lastly by providing the pocket 23 in the 35 last it is possible to apply the short screw 22 to the sole portion of the shoe and to perform the necessary operations upon the sole portion without interference from said screw.

It is obvious that those skilled in the art may 40 vary the details of construction and arrangements of parts constituting the apparatus, as well as vary the steps and combinations of steps constituting the method, without departing from the spirit of this invention, and therefore it is 45 not desired to be limited to the foregoing disclosure except as may be demanded by the claims.

What is claimed is:

1. The method of securing a heel to the sole of a shoe which consists in positioning the heel on 50 the sole; applying pressure to the combined heel and sole; and securing the heel and sole while the pressure is so applied, by independent tension applied through the base of the heel.

2. The method of securing a heel to the sole of a shoe by a plurality of tensioning members which consists in applying one of the members to the sole portion of the shoe in such manner as to permit ready operations upon the sole portion during the building-up of the shoe and applying a second 65 member to the first member after the shoe is built up; applying a third member to the heel and second member and positioning the heel on the sole; applying pressure to the combined heel and sole; and securing all of the members while the 70 pressure is so applied, by independent tension applied through the base of the heel.
